ROBERT PARKS, OF PHILADELPHIA, PENNSYLVANIA.

Letters Patent No. 70,464, dated November 5, 1867.

IMPROVEMENT IN TAGS.

The Schedule referred to in these Letters Patent and making part of the same.

TO ALL WHOM IT MAY CONCERN:

Be it known that I, ROBERT PARKS, of the city and county of Philadelphia, and State of Pennsylvania, have invented a new and useful Improved Tag; and I do hereby declare the following to be a clear and exact description of the nature thereof, sufficient to enable others skilled in the art to which it appertains to fully understand and use the same; reference being had to the accompanying drawings, making part of this specification, in which—

Figure 1 is a side elevation of the cut or slit blank from which the tag is made.

Figure 2 is a view showing the tag complete.

Figure 3 is an elevation of a tag-blank, illustrating a modification thereof.

Similar letters of reference indicate corresponding parts in the several figures.

My invention consists in constructing a tag in a novel and simple manner, whereby strength and cheapness are combined. One end is cut or slitted so as to leave three flaps. The middle one may be cut out entirely, or retained and folded over to lie on the card. The two side flaps are then turned or folded inwardly, and will partly overlap each other. Should the middle flap be retained the end of the card will have four thicknesses of material, and otherwise but three, and in either case the card will be reinforced in an exceedingly strong and durable manner, as will be hereinafter more fully described.

In the drawings, A represents the body of the card or tag. One end is cut or slitted from its edge to a certain distance therefrom, as shown at *a a*, thus leaving three flaps *b c d*. The middle flap *c* is then folded on the body of the tag. One of the side flaps, *b* or *c*, is then folded downwardly, and towards the other side, and over flap *c*. The other side flap, *c* or *b*, is likewise folded and lies on top of the other. The three flaps thus lie snugly against the body of the tag, and are readily pierced or punched, and, if desired, may be eyeleted. The inner edges of the side flaps will correspond to the top of the tag, and exactly fit the same when folded. Their outer edges will also correspond to each other. It will be perceived that there is no waste of material. The slits are quickly made and the flaps readily folded. The top edges of the tag, as completed or folded, are protected against abrasion or wear and tear, and as nearly all the strain is at the top, protection is afforded thereto, as well as on the hole or eyelet, by the reinforcement I adopt. Besides this, when the tag is affixed to any article, it is liable to be jammed, or be caught in between the same and others, as is common in express or freight transportation, and as very little care or gentleness is exercised in releasing the tag, it is torn or cut, or otherwise detached, to the great annoyance and inconvenience of those concerned. My invention will remedy this evil, as the tag will withstand considerable strain or pulling.

A great advantage has been noticed in cutting off the corners of cards when used for addresses, because they allow more play to the card, and thus decrease the chances of wear and tear. Besides this, the right-angled corners greatly incommod the operation of affixing the card to whatever desired. Any one who has used the two kinds will understand the advantages or disadvantages as described. Now I acquire this advantage and produce the desired shape by my mode of constructing the tag. The middle flap may be glued or gummed to the body, and the side flaps be glued together and on the middle piece. In fact, all or some of the flaps may be gummed or glued to each other and to the body of the tag, as desired. In lieu of the above, the middle piece *c* may be dispensed with by being cut off, and only the side pieces or flaps *b* and *d* be employed, (see fig. 3.) They will lie snugly upon each other, but make only three folds or thicknesses. Another modification is by folding the side pieces first on the body, and then the middle one afterwards, so as to overlap the side pieces. It is desirable to cut the middle flap in square form, then the side pieces or flaps will exactly fit or lie properly in their places. I desire to manufacture the tags, whether cut from a continuous roll or separate sheets, and do not limit myself to material, intending to employ paper, muslin, pasteboard, muslin and paper combined, or whatever is suitable. My tag can be readily produced by machinery, and is cheap, durable, and strong.

Having thus described my invention, what I claim as new, and desire to secure by Letters Patent, is—

The tag A, constructed with cuts or incisions *a a*, and parts *b c d* or *b d*, folded over and secured substantially as and for the purposes set forth.

To the above I have signed my name this sixteenth day of August, 1867.

ROBERT PARKS.
